UNITED STATES PATENT OFFICE.

EMILIO PASCUCCI, OF CORNING, NEW YORK, ASSIGNOR TO CORNING GLASS WORKS,
OF CORNING, NEW YORK, A CORPORATION OF NEW YORK.

MOLD.

Application filed April 13, 1921. Serial No. 461,066.

To all whom it may concern:

Be it known that I, EMILIO PASCUCCI, a citizen of the United States of America, and a resident of Corning, New York, have invented certain new and useful Improvements in Molds, of which the following is a specification.

This invention relates to the manufacture of spark plugs having cores of pressed glass, and one object is to provide a mold for forming the cores wherein the parts constituting the molding cavity cooperate in an improved manner, and wherein means of improved construction are employed for holding the metal parts of the spark plug during the forming operation.

A further feature of this invention is in the construction of the mold with insulated sections for the purpose of enabling an electric current to be passed through the electrode, so as to heat it to insure a joint between it and the glass.

The invention consists in the novel features of construction and in the combination of parts hereinafter fully described and claimed.

In the accompanying drawings:—

Figure I, is a vertical section through a mold for use in the manufacture of spark plug cores, the parts being shown assembled and ready for the introduction of a charge of molten glass, the mold plunger being omitted;

Fig. II, is a vertical section taken on the line II—II of Figure I, showing the glass pressed in the mold cavity;

Fig. III, is a horizontal section through the upper portion of the mold taken on the line III—III of Figure I;

Fig. IV, is a horizontal section taken on the line IV—IV of Figure I, and

Fig. V, is an inverted view of the upper portion of the mold, the parts thereof being separated slightly.

The spark plug core which is adapted to be made in the mold forming the subject matter of this invention comprises a central electrode 1 having an upper portion 2 formed of some low expansion metal of relatively small diameter which can be sealed in the glass of which the core is made, and a

lower portion 3 larger in diameter and of some metal which stands up under the conditions to which the spark points are subjected, the two parts of the electrode being welded, or otherwise firmly seamed together. Fastened to the upper extremity of the electrode portion 2 is a wiring terminal in the form of a cap 4. The core is molded into form around the central electrode 1 and within the cap 4, and also within a band 5 which surrounds its central portion, the interior of the band 5 having rounded annular corrugations 6 therein to anchor the glass within the band. The external contour of the core may closely approach, or be identical with standard practice.

The mold comprises a base portion 7, and a top portion 8 that is made of separable, and preferably, of hinged halves. The base 7 has in its upper face a recess 9 forming the lower part of the mold cavity. The upper end of this cavity has a diameter sufficient to receive the lower half of the band 5, a shoulder being formed in the recess 9, immediately below such enlarged diameter, to form a seat for the band. In practice, a block 10 may be inserted in the base 7, and the center of this block is recessed with a contour to form the tip portion of 80 the core.

The hinged halves forming the top portion 8 of the mold are similarly formed and they each have a central recess 12 registering, when the mold parts are assembled, 85 with the recess 9 in the base. The recess 12 is large enough at its bottom end to take in the upper half of the band 5, the upper portion thereof being of the general contour desired for the core above the band. 90

In order to hold the top portion of the mold in place on the base, the upper surface of the base surrounding the recess 9 therein is formed into a boss 13, having undercut walls 14, and the top portion 8 of the mold 95 has a similarly shaped recess formed in its bottom, and when its two halves are assembled together on the base, and locked against separation, it will be firmly anchored on the base.

The halves of the top portion of the mold are shown as provided with pieces in the

form of rectangular blocks 15 that are inserted therein and held in place by means of screws (see Fig. V), a layer of insulating material 16, such as mica, being interposed 5 between the contacting surfaces of the blocks and halves of the top section. In these blocks is preferably formed the central recess 12 for receiving the upper half of the band 5 and also the lower part of the portion 10 of the cavity forming the core above the band 5. The cavity is extended above the band 5 and its upper portion, which is within the top portion of the mold, is adapted to receive and support the cap 4 on the 15 upper end of the electrode.

A font cavity 17 is formed in the upper part of the top section, and communicates by sprue passages 18 with the core cavity, entering the same below the space occupied 20 by the cap. In the drawings, these passages are shown as formed in part in the blocks 15.

The construction of the top portion of the mold is such, that when the hinged sections thereof are assembled on the base, with the 25 metal parts of the spark plug core positioned in the mold cavity, the part of the mold in which is placed the cap 4 will be separated by the insulation 16 from the part thereof in which the band 5 is placed, the 30 band 5 being supported by the recess 9 in the base portion 7 and the recess 12 formed in blocks 15 of the top mold section.

The base portion 7 of the mold, below the recess 9 therein, is bored axially of the mold 35 cavity, as at 19, and also bored radially thereto. In the latter bore is contained a clamping screw 20.

In forming the core, the electrode, with the cap 4 fastened thereon, has its lower 40 end inserted in the vertical bore 19 of the lower section, a plate 21 on the bottom of the section serving to properly position it, and is clamped in place by the screw 20. The band 5 is slipped over the upper extremity of the electrode and inserted in the 45 enlarged upper end of the recess 9 in the lower section 7. The halves of the upper section are then closed around the boss 13 on the lower section.

50 The electrode now has its lower end firmly held in the lower section, and its upper end in the upper section. If the upper and lower mold sections are now included as a part of an electric circuit fed

55 from a proper source of energy by means of wires 22 and 23 that are respectively attached to the upper and lower sections, current will flow through the electrode, the insulating layer 16 restraining it to this path.

60 The current should be of sufficient volume to heat to incandescence the electrode, whereby gases occluded therein will be driven off. After this action has taken place, and while the electrode is still hot,

65 glass which has been placed in the font

cavity 17 in any proper way, is forced by the action of a plunger 24 to flow through the sprue passages into the mold cavity formed by the recesses in the top and bottom sections. In doing this, it flows up 70 into the cap 4, and around the electrode, and within the band 5, to which it unites itself by a joint in the nature of a weld. As the occluded gases have been drawn out of the electrode, it will be found that the 75 joint between the electrode and the glass is good, and free of air bubbles which would otherwise be present and tend to leakage. The glass having set, the mold is opened and the glass with its surrounding band and 80 enclosed electrode taken out. The sprues and excess glass in the font cavity are then removed by breaking them off and grinding.

Having thus described my invention what I claim as new is:—

85 1. A mold for forming glass articles on metal, comprising a plurality of parts, each adapted to hold an end of the metal on which the glass is to be welded, the said mold parts being insulated from each other 90 but forming a continuous mold cavity.

95 2. A mold for glass articles, comprising a plurality of parts forming a molding cavity, two of said parts having means thereon to clamp an electrode, around which glass is to be welded, and means for insulating the two said parts from each other.

100 3. A glass spark plug core mold having a molding cavity provided with a recess for retaining in position the terminal cap on the upper end of the electrode, means for clamping the lower end of the electrode in the mold body, and means for heating the electrode when it is clamped in position.

105 4. A mold having a molding cavity therein and having means whereby a metal part may be positioned in the cavity with its ends in electrical contact with the mold, means for electrically insulating that portion of the mold having electrical contact 110 with one end of the piece of metal from that portion of mold having electrical contact with the other end of the piece of metal, whereby an electrical current may be passed through the mold and metal part, for driving off occluded gases from the metal, and means for feeding molten glass into the mold cavity.

115 5. A mold having a molded cavity and having molding parts electrically insulated from each other, and having means whereby a metal part may be positioned in the cavity with its opposite ends in electrical contact with the said electrically insulated molding parts, whereby an electrical current may be passed through the insulated molding parts and through the metal while the latter is in position in the molding cavity.

120 6. A mold of the class described compris- 125

ing a base portion and an upper portion adapted to be assembled on the base, said upper portion consisting of hinged halves, means formed on the base for anchoring the 5 upper portion, a cavity formed in part in the base and in part in the upper portion, an electrode centrally positioned axially in said cavity and retained by the upper and base portions of the mold, and means for insulating the upper portion of the mold 10 from the base portion thereof.

In testimony whereof, I hereunto sign my name.

EMILIO PASCUCCI.
